UNITED STATES PATENT OFFICE.

ROYAL L. SCOVILLE, OF SEWICKLEY, PENNSYLVANIA.

PROJECTILE.

1,203,059.

Specification of Letters Patent. Patented Oct. 31, 1916.

Application filed January 22, 1916. Serial No. 73,710.

To all whom it may concern:

Be it known that I, ROYAL L. SCOVILLE, residing at Sewickley, in the county of Allegheny and State of Pennsylvania, a citizen of the United States, have invented or discovered certain new and useful Improvements in Projectiles, of which improvements the following is a specification.

My invention relates to improvements in projectiles and has particularly to do with the fuse-block of a projectile: such a fuse-block as that shown in my application for United States Letters Patent filed November 1, 1915, Serial No. 59,013, applied to a hand-grenade.

The objects of my present invention are economy of material, saving in weight in a portion of the structure where weight is of no value that weight may be increased elsewhere, and the protection of delicate and sensitive parts from accident and injury.

A hand-grenade provided with a fuse-block of my present invention is shown in the accompanying drawings.

Figure 1 is a view of the grenade in medial longitudinal section; Fig. 2 is a view in transverse section on a plane indicated by the line II—II, Fig. 1. In Fig. 1 the fuse-block is shown in medial section, and in Fig. 2 it is shown in plan view from above. Figs. 3 and 4 are sectional views of the fuse-block detached, the planes of section being indicated by the line III—III, Fig. 4, and IV—IV, Fig. 3, respectively.

The grenade consists essentially of a casing 1, having formed within it an open-ended burster-charge chamber, a fuse-block 2, filling the otherwise open end of the burster-charge chamber, and a cover plate 3, engaging the casing and (when the parts are assembled) securing the fuse-block in place. The fuse-block carries the primer and the cover plate the firing-pin; and, at the proper instant in the use of the grenade, the firing-pin is caused to impinge upon the primer and so to fire the train which leads to the burster charge.

It is with the fuse-block that the present invention has to do; and, having now pointed out its relative position in the structure as a whole, I shall confine attention wholly to it.

The fuse-block is, in shape, a short cylinder or thick disk. It fits easily in, and may be slipped in and out in its seat in, the otherwise open end of the burster-charge cham-

ber. It is invertible, and may be seated with either one of its opposite faces inward.

In one of its opposite faces the fuse-block is provided with a suitable seat 4 for a percussion cap *c*, and in the other face it is provided with a recess 5 for a detonator *d*. It will of course be understood that the seat for the percussion cap is so arranged in the face of the fuse-block, with relation to the arrangement of the firing-pin in cover plate 3, that, when the parts are assembled (the fuse-block being in its operative, as distinguished from its inverted and inoperative position), the percussion cap and the firing-pin will be in proper relative positions. Preferably this relative arrangement is such that the seat for the percussion cap is central in the face of the fuse-block, as the drawings show it.

In the same face of the fuse-block with the seat 4 for the primer (that is, the outer face when the block is in operative position) is formed a groove or channel 10 for a time-fuse; this channel 10, as is best shown in Fig. 2, extends in a substantially circular arrangement around the periphery of the fuse-block, the percussion-cap seat being at the center. The channel 10 is provided with a cover strip 26, and when this cover strip is applied the channel becomes a closed duct. A duct or flashway 9 leads from the percussion-cap seat 4 to the fuse channel 10 at one end, and at the other end the channel 10 terminates in a perforation (best shown in Fig. 4) which extends through the fuse-block and opens on the opposite side of the block to the detonator recess 5. A second duct or flashway 12 leads from the percussion-cap seat 4 to the fuse channel 10, and opens to the fuse channel at a point intermediate its extent; and in this second flashway 12 is arranged a removable obstruction, here shown in the form of a screwed-in stud 13. This stud may be adapted to be wholly removed in order to leave the flashway unobstructed, or it may have a perforation through it and adapted by being turned through an angle of 90° to either close the flashway or leave it open.

The detonator seat 5 is, as has been explained, arranged in the face of the fuse-block opposite the primer seat—the inner face, when the fuse-block is in operative position. It is an open channel, of substantial length and is preferably arranged (as best shown in Fig. 3) to one side from an

exact diametrical position. At one end this channel 5 opens through the rim of the disk, at the other end the perforation already mentioned opens—the perforation, namely, 5 which leads from the fuse channel 10. The non-diametrical arrangement of the detonator recess is in coördination with the central arrangement of the percussion cap (and, accordingly, of the firing-pin) which 10 is shown in the drawings, and it will be observed that this is an arrangement in positions of relative non-correspondence—that is to say, the detonator when turned outward will occupy a position different from 15 that of the percussion-cap seat when it is turned outward. The detonator is placed to one side of the center of the disk, to the end that, when the disk is introduced in inverted position, with detonator outward 20 (the position for shipment) accidental release of the firing-pin can have no effect, to fire the detonator. A central recess 23 may be provided in that face of the fuse-block which bears the detonator, for a purpose 25 presently to be stated.

In my earlier application referred to I showed and described a booster charge, designed to serve as an element in the train of detonation, intermediate between detonator 30 and burster charge. Such a booster charge, although it may be employed, is not essential; and I have omitted it from this grenade which I here show and describe. The detonator seat 5 is, as I have explained, 35 open to the burster-charge chamber, and, using a detonator capsule of now familiar form and size loaded with fulminate of mercury, and a burster charge of trinitrotoluene in crystalline form, detonation will 40 be effected.

The fuse-block is reduced to a minimum of weight compatible with safety by cutting away superfluous metal, as is indicated in the spaces 27 which interrupt the continuity 45 of the disk. The block will, when made commercially, be a casting, and of course the cutting away which I speak of is what the designer would speak of as a cutting away; there is no cutting away in fact, but 50 the mold is so shaped so as to leave these lacunæ in the molded disk. The purpose will readily be understood. The fuse-block is practically valueless to be fragmented on explosion into effective missiles; the 55 weight of the structure as a whole is limited to such a weight as a man can hurl to considerable distance; and it is desirable to make the casing (and the cover plate 3) as heavy as possible, for they are the missile-forming parts. Accordingly, given a fixed maximum weight for the whole, whatever is subtracted from the fuse-block may be 60 added to the casing.

The drawings show the fuse-block loaded. 65 In loading, a length of time-fuse is laid in

channel 10 from end to end and extending through the perforation and into the detonator recess 5. When the time-fuse has been put in place the cover strip 26 is applied to channel 10. (Being of light 70 weight, this plate may easily be secured by frictional engagement of its edges with the edges of the seat rabbeted to receive it in the edges of the channel 10.) When the cover strip 26 is in place, the seam between 75 it and the edges of channel 10 may be coated over with suitable moisture-proof shellac or other coating material. The percussion cap 4 is set in its seat in usual manner. The detonator is slipped to place, the open 80 end of the capsule taking over the otherwise free end of the time fuse, in the manner indicated in Figs. 3 and 4. Ordinarily the detonator is not applied before shipment, but only when the grenade is about 85 to be used.

The fuse-block with time-fuse in place and cover strip applied and sealed (and, ordinarily, a percussion cap on the seat 4) is ready to be assembled for shipment. The 90 block is introduced in the mouth of the previously filled burster-charge chamber of a grenade in inverted position—that is, with the percussion cap inward and the detonator outward—and the cover plate 3 is applied. The detonator is the sensitive element of the machine, and is liable to premature detonation, if through chance it be subjected to some more than ordinarily severe 95 shock. But, with the fuse block inverted, 100 the detonator, even though accidentally fired, is ineffective to cause detonation of the burster charge. And here it may be noted that, because of the non-diametrical position of the detonator in the face of the 105 fuse block, an accidental operation of the firing-pin (which is arranged in a central position) cannot affect the detonator. The released firing-pin will merely enter the recess 23 formed in the face of the fuse-block 110 to receive it. Indeed, it may be preferable to ship the grenade with the firing-pin in released position, resting in this recess 23, and to "cock" it when and not until the 115 grenade is about to be used. The detonator capsule will preferably be shipped separately.

When a grenade is to be used, the firing-pin is cocked, the cover plate 3 is removed, the fuse-block is taken out, a detonator is 120 applied in the recess 5 formed to receive it. The fuse-block is then replaced in normal operative position, detonator inward and percussion cap outward. The position of the screw-plug 13 is then looked to; if a 125 short time interval be desired between the firing of the cap and detonation of the burster charge (as, for instance, when the grenade is to be used in the manner herein primarily contemplated, as a hand-grenade), 130

the screw plug 13 will be turned to position leaving flashway 12 open; but if a longer time interval be desired, flashway 12 will be closed by screw plug 13, in which case 5 the entire length of the time-fuse will be brought into the train of operation. When the fuse-block has thus been made ready the cover plate is screwed on again. The parts are then in the position shown in Fig. 1 of 10 the drawings.

Operation need not be described, further than to say that when thereafter, incidentally to the hurling, the flight or the impact of the grenade, the firing-pin is released, 15 it impinges on and fires the percussion cap *c*, and then the train of detonation is started. The flash spouts through flashway 9 and (if it be open) through flashway 12 also, and ignites the time-fuse *f*. Ignition 20 traverses the time fuse to the detonator, and detonation follows—primarily of the fulminate of mercury and through it of the trinitrotoluene.

I claim herein as my invention:

25 1. In a projectile the combination with an otherwise open-mouthed burster-charge chamber of a fuse-block filling the mouth of said chamber, said fuse-block being provided on its inner face with a detonator recess and 30 on its outer face with a percussion-cap seat and a channel for a time-fuse, and said time-fuse channel communicating both with the percussion-cap seat and with the detonator recess, and a cover strip applicable as a 35 closure over said time fuse channel.

2. In a projectile the combination with

an otherwise open-mouthed burster-charge chamber of a fuse-block filling the mouth of said chamber and invertible in such position, said fuse-block being provided on one face 40 with a percussion-cap seat and on the opposite face with a detonator recess, said percussion-cap seat and said detonator recess being arranged in the two faces of the fuse-block in positions of non-correspondence. 45

3. In a projectile the combination with an otherwise open-mouthed burster-charge chamber of a fuse-block filling the mouth of said chamber and invertible in such position, said fuse-block being provided on one face 50 with a centrally arranged percussion cap seat and on the opposite face with an elongate detonator recess such recess not crossing the center of the block.

4. In a projectile the combination with an otherwise open-mouthed burster-charge chamber of a disk-shaped fuse-block filling the mouth of said chamber, said fuse-block being provided on one face with a percussion-cap seat and on the other face with a 60 detonator recess and with a time fuse duct extending between said seat and said recess, the said disk-shaped fuse-block being cut away in that portion not so specially shaped as aforesaid. 65

In testimony whereof I have hereunto set my hand.

ROYAL L. SCOVILLE.
